United States Patent

Des. 239,655
Patented Apr. 20, 1976

239,655

ORGAN

Thomas E. Kimble, Covington, Ky., assignor to
D. H. Baldwin Company

Filed Apr. 30, 1974, Ser. No. 465,520

Term of patent 14 years

Int. Cl. D17—01

U.S. Cl. D56—2

Fig. 1

FIG. 2**FIG. 3**

FIG. 1 is a front, top and left side perspective view of an organ showing my new design;

FIG. 2 is a front elevational view; and

FIG. 3 is a right side elevational view.

The rear of the organ is conventional. The rear section of the top is planar and unornamented. The pattern on the fabric covering the lower front and side panels is continuous throughout these areas.

I claim:

The ornamental design for an organ, as shown and described.
